UNITED STATES PATENT OFFICE.

JOHN T. HARRISON, OF ASBURY PARK, NEW JERSEY.

NON-REFILLABLE BOTTLE.

1,270,152.

Specification of Letters Patent. Patented June 18, 1918.

Application filed August 31, 1917. Serial No. 189,163.

To all whom it may concern:

Be it known that I, JOHN T. HARRISON, a citizen of the United States, residing at Asbury Park, in the county of Monmouth and State of New Jersey, have invented new and useful Improvements in Non-Refillable Bottles, of which the following is a specification.

This invention relates to improvements in bottles of the non-refillable type and aims to provide a bottle which will be automatically destroyed as soon as the contents thereof have been fully removed.

An object of the invention is to provide a movable bottom for the bottle, which will be automatically raised as the contents of the bottle are removed, means being provided for limiting the amount removed at each operation, said means operating novel means for raising the bottom in proportion.

Another object is to provide novel means for destroying the bottle when emptied, the means employed being automatically operated so that when the movable bottom reaches its highest point the bottle is completely emptied, the casing which surrounds the bottle preventing injury or the breaking of the glass.

A still further object is to provide novel holding and releasing means for the bottle destroying means, so that the said destroying means will be held inactive until the contents of the bottle have been fully removed.

With the above and other objects in view, the invention consists of the following novel combination and arrangement of parts, hereinafter more fully described and illustrated in the accompanying drawings, in which—

Figure 1 is a longitudinal sectional view through a bottle embodying the present invention;

Fig. 2 is a plan view of the same;

Fig. 3 is a fragmentary sectional view of the upper portion of the bottle showing the closure in a position opposite that shown in Fig. 1; and

Fig. 4 is a cross-sectional view on the line 4—4 of Fig. 1.

Referring to the drawings in detail, there is illustrated a bottle composed of glass or other suitable material, which comprises a body portion 10 and a neck portion 11. The body portion of the bottle is preferably cylindrical in shape, the upper end 12 of the body joining the sides thereof at a

right angle, so that this end is substantially flat. The neck 11 is cylindrical in shape and rises concentrically on the upper end 12, an opening 13 establishing communication between the neck and the body portion.

The bottle is open at its lower end, this end being designed to be closed by means of the movable member 14, which preferably consists of a metal disk 15, a rubber disk 16, a cork layer 17 and a glass disk 18, these members being secured together in the order named and being of a diameter to provide air and water tight joints between the edges thereof and the inside of the body member.

Secured to the bottom of the movable member 14 by means of a lug 19, is a coil spring 20, the end of the spring opposite that secured to the end of the lug 19 being secured within a rotatable cylinder 21, mounted for movement beneath the bottom of the bottle. The cylinder 21 is mounted within the chamber 22, one wall 23 of which serves to close the open bottom end of the bottle, the spring 20 passing through a guiding sleeve 24 located in this wall. By rotating the cylinder 21 the spring is fed through the sleeve 24, to raise or lower the member 14, that portion of the springs within the cylinder being closely coiled therein, while the opposite portion which extends within the body portion of the bottle serving to resiliently support the member 14. In order to prevent the said member from turning, there is formed in the edge thereof a notch 25, which is adapted to operate over the longitudinally arranged bead 26 provided with in the bottle.

In order to rotate the cylinder 21 the said cylinder is provided with a ring gear 27, which is adapted to engage the pinion 28, mounted upon the short shaft 29 within the chamber 22. Another pinion 30 which engages the pinion 28 is carried by a longitudinally disposed shaft 31, mounted in a sleeve 32 provided with a metallic casing 33, which casing acts to prevent the broken glass from flying about when the bottle is destroyed, as will be hereinafter explained. The chamber 22 forms a part of this casing. In order to permit the contents of the bottle to be viewed, so as to ascertain the amount therein, the casing 33 is provided with a sight opening 34.

The shaft 31 which carries the pinion 30, is also provided upon its opposite end with a pinion 35, which engages an idler 36

mounted upon a suitable bearing 37 provided in the extension of the casing 33.

It is the purpose of the invention to provide means whereby the member 14 of the bottle will be automatically moved upward in proportion to the amount of liquid removed from the bottle and to this end the neck of the bottle is provided with means whereby the amount removed at each operation 10 may be regulated. This consists of providing within the neck 11 a rotatable cylinder 37, the ends 38 of which are formed with openings 39, the said openings being located near the periphery of the cylinder 15 and upon diametrically opposite sides. One of the openings 39 is designed to be brought into register with the opening 13, while the other opening is designed to be brought into register with the opening 40 formed in the 20 casing extension previously referred to. The openings 13 and 40 are in vertical alinement, so that when one of the openings 39 registers with the opening 13, the openings at the opposite end of the neck will be closed and vice versa, so that only a predetermined 25 amount of liquid can be dispensed with at one operation.

The cylinder 37 is provided from one end with an annular flange 41, the outer edge of 30 which is provided with gear teeth 42, which are adapted to engage the idler 36 to drive the shaft 35 and operate the cylinder 21, so that at each operation of the cylinder 37 for the purpose of moving a portion of the 35 contents of the bottle, the cylinder 21 may be rotated to feed the spring 20 through the sleeve 24.

Located upon the bottom of the member 14 are a pair of oppositely disposed bearing 40 lugs 43, within which is mounted for movement the rod 44, each of the said rods carrying at one end plungers 45. Interposed between these plungers and the lugs 43 are coil springs 46, the purpose of which is to 45 normally force the plungers 45 into contact with the inside of the bottle. The plungers 45 are retained in an inactive position through the medium of a flexible member 47, one end of each of the rods 44 being secured 50 to one end of the member 47, the said member passing over rollers or guides 48 and having its looped end engaging with the notch 49 formed in one end of the lever 50. This lever is pivoted at 51 upon the member 55 14 and is formed at its opposite end with an angularly disposed lip 52, which is adapted to normally ride against the inner side of the bottle, the said lever being held in such engagement through the action of the 60 springs 46, so that the plungers 45 are normally in a retracted position. With the member 14 moving upward, the angularly disposed lip 52 of the lever 50 will engage a notch 53 formed in the body portion of 65 the bottle, permitting a swinging inward of

the notched end of the lever, thereby releasing the member 47, so that the springs 46 will cause the plungers 45 to fly against the sides of the body portion of the bottle and destroy the same.

Various changes in the form, proportion and details of construction may be made in the invention without departing from the spirit thereof or sacrificing any of the advantages of the same and the right is reserved to make such changes.

Having described the invention, what is claimed is:

1. A bottle of the class described embodying a member mounted for vertical movement within said bottle, means for controlling the movement of said member and means carried by said member for destroying the bottle when the member reaches a predetermined position.

2. A bottle of the class described embodying a member mounted for vertical movement therein, means for controlling the movement of said member and means including spring actuated elements for destroying the bottle when the member reaches a predetermined position.

3. A bottle of the class described embodying a member mounted for vertical movement therein, means for controlling the movement of said member, normally retracted spring actuated elements carried by said member and means for automatically releasing said elements when the member reaches a predetermined position.

4. A bottle of the class described embodying a member mounted for vertical movement therein, means for controlling the movement of said member, normally retracted spring actuated elements carried by said member, means including a trigger carried by said member for maintaining said elements in a retracted position and means for automatically releasing said trigger when the member reaches a predetermined position.

5. A bottle of the class described embodying a member mounted for vertical movement within said bottle, means carried by said member for destroying said bottle when the member reaches a predetermined position, a closure for said bottle and means operated by the opening of said closure for regulating the movement of the member.

6. A bottle of the class described embodying a member mounted for vertical movement within said bottle, means carried by said member for destroying said bottle when the member reaches a predetermined position, a closure for said bottle and means including a gear operated by said closure for regulating the movement of said member.

7. A bottle of the class described embodying a resiliently mounted member capable of movement therein, means for controlling the

movement of said member and means carried by said member for destroying the bottle when the member reaches a predetermined position.

5 8. A bottle of the class described embodying a member mounted for vertical movement therein, means for controlling the movement of said member and means car-

ried by said member for destroying the bottle when the member reaches a predetermined position and a spring located beneath said member and movable through an opening in the bottle for forcing said member upward. 10

In testimony whereof I affix my signature. 15
JOHN T. HARRISON.
